[57] CLAIM

The ornamental design for a bag organizer, substantially
as shown and described.

DESCRIPTION

FIG. 1 is a perspective view of a bag organizer showing
my new design;

FIG. 2 is an enlarged top plan view thereof;

FIG. 3 is an enlarged front elevational view thereof;
FIG. 4 is an enlarged fragmentary front elevational
view of a second embodiment of the design of FIG. 1,
the only difference being the configuration of the eyes;
FIG. 5 is an enlarged right side elevational view of
FIG. 1;

FIG. 6 is a perspective view of a third embodiment of
the design of FIG. 1;

FIG. 7 is an enlarged top plan view of FIG. 6;

FIG. 8 is an enlarged front elevational view of FIG. 6;
FIG. 9 is an enlarged right side elevational view of
FIG. 6.
